UNITED STATES PATENT OFFICE.

JOHN J. BERRIGAN, OF ORANGE, NEW JERSEY, ASSIGNOR TO HENRY R. WORTHINGTON,
A CORPORATION OF NEW JERSEY.

PRESSING APPARATUS.

1,336,341.

Specification of Letters Patent.

Patented Apr. 6, 1920.

Application filed March 9, 1918. Serial No. 221,378.

To all whom it may concern:

Be it known that I, JOHN J. BERRIGAN, a citizen of the United States, residing at Orange, county of Essex, and State of New Jersey, have invented certain new and useful Improvements in Pressing Apparatus, fully described and represented in the following specification and the accompanying drawings, forming a part of the same.

- 10 This invention relates to improvements in pressing apparatus and is particularly applicable to that type of pressing apparatus set forth in applicant's former Patents 1,130,701, 1,130,878, 1,130,879 and 1,131,032.
- 15 The structures referred to include, in general, a pair of coöoperating pressing members mounted for a general up and down movement, means for causing the pressing members to mutually approach and recede as 20 they descend and rise, and means, such as a fluid pressure cylinder and piston, for raising the pressing members and checking their gravitational descent. The present invention provides pressing apparatus of this type by 25 which there is made possible a material reduction in the weight of the press, in the cost of manufacture, and in the expense of installation.

With the above objects, and other objects 30 which will be obvious to those skilled in the art, in view, the invention consists in the features of construction and combinations of parts which will be first described in connection with the accompanying drawings, 35 illustrating the preferred embodiment of the invention, and then more particularly pointed out in the claims.

In the drawings—

40 Figure 1 is a view in side elevation, with parts broken away, of a pressing apparatus constructed in accordance with the invention, showing the parts out of pressing phase;

45 Fig. 2 is a similar view showing the parts at the end of the pressing operation;

Fig. 3 is a view in end elevation, with parts broken away, taken from the right-hand side of Fig. 2;

50 Fig. 4 is an enlarged partial vertical sectional view; and

Fig. 5 is a face view, with parts broken away, of one of the supplemental pressing partitions.

Referring to the drawings, the apparatus

includes a pair of coöoperating pressing members or platens 10, 11, mounted as herein-after described. Means is provided for pivotally connecting these press platens together for relative angular movement, the construction preferably being such that the angular relation of the platens may be varied and the distance separating them may have a wide range. Although capable of various constructions, in the present embodiment, in the lower corners of the platens 10, 11 are pivotally journaled pins 12 having block portions 13 through which passes a long rod 14. The rod 14 is threaded and a hand wheel 15 is provided, and by turning the wheel the angle between the platens 16 may be varied as desired. In the embodiment here illustrated, this connecting means is provided, in duplicate, on each side of the press.

The press platens 10, 11 are pivoted for 75 angular or rocking movement toward and from each other, and in the type of press shown this angular movement is combined with an up and down movement, so that when raised to a certain position and released the platens may descend and move 80 angularly under the action of gravity, and means are provided for causing the press platens to mutually approach and recede from each other during such descent and 85 rise. Although this movement may be secured by various constructions, in that here illustrated the press platens are pivotally mounted in lever or link members having 90 an angular movement about fixed fulcrums, these fulcrums being in a plane lying below the plane through the points where the platens are pivoted to said members. As shown, the press platens 10 and 11 are each provided with a cross shaft 16, the ends of 95 which form horizontally projecting trunnions. These trunnions are journaled or pivotally mounted in lever members 17, 18 of the configuration shown in Fig. 1. To pivotally mount the levers, each pair is 100 secured to a cross shaft 19 which is journaled in a stationary boxing formed by pedestals or supporting members 20. These pedestals are secured to the floor or other base 21 and are connected lengthwise of 105 the press by tension rods 22. These tension rods pass through holes in the supporting members above and below the fulcrums of

the respective levers, the rods being screw-threaded and provided with inside and outside nuts 23 which serve to clamp the boxings between them.

- 5 It will be seen that the weight of the pressing members 10, 11 will tend to swing the lever members downward and as these have fixed fulcrums and hence have an angular movement with respect to their fulcrums, the pressing members are caused to move toward each other as they descend, so that any material between them will be subjected to a pressing action by this movement, as well as by the angular or rocking movement of the platens which forces together the partitions and bags from their inclined or spread position, as shown in Fig. 1, into their vertical compressed position shown in Fig. 2.
- 10 20 The lever members on each side of the press are tied together by a long link 24 which is pivoted to the upper corner of one lever member and the lower corner of the other. For purpose of adjustment, one end 25 of the link is provided with a plurality of mounting holes 26.

The proportioning and adjustment of the parts are intended to be such, under the best conditions of operation, that when material is in place between the pressing members, the latter will have such a limit of downward movement that their pivotal points and fulcrums lie in substantially the same horizontal plane—or, at least, the pivotal points will be only slightly above the fulcrum plane. Furthermore, at this limit, the pressing faces of the pressing members should lie in substantially vertical planes.

The invention includes means, mounted 40 to be free from the strain and weight of the press, for controlling the pressing members. That is to say, means for raising the pressing members and for regulating their gravitational descent. This controlling means has a 45 floating connection with the associated parts and may have operating connection with the lever members and act on the pressing members through them. Although capable of various constructions, in that 50 shown the controlling means includes a fluid pressure cylinder 27 and piston 28. Cylinder and piston lie in a horizontal plane and are pivotally connected with the lever members so as to float therebetween. To this 55 end, the cylinder 27 has an extension or lug 29 which is pivotally connected to the lower corner of the lever member, and the outer end of the piston rod 28 has a lug 30 pivoted to the lower corner of the opposite 60 lever member 17. To support the inner end of the cylinder, the latter is provided with a bar 31 which rests on and slides over the lug 30. As appears in the drawings, this 65 controlling means is duplicated, one set being provided on each side of the apparatus.

The controlling means is capable of being used to raise the press members, to check their descent by operating as a controllable power brake, and to apply an extraneous force supplemental to gravity for increasing the pressure on the material being treated. In the present embodiment, associated with each cylinder is a pipe 33 provided at each end with valves 34, 35 connected with couplings 36 leading to the cylinder. Between the valves 34, 35 is a T-coupling 37 connecting with a fluid-supply pipe 38. At each end of the cylinder are outlet valves 39, 40.

Fig. 2 represents the press subsequent to a pressing operation. The water supply being turned on, valve 34 open and valve 35 closed, water or other fluid under pressure is admitted to the cylinder behind the piston head and drives the piston to the left (Figs. 1 and 2). This movement swings the levers in a manner to raise the parts to the position of Fig. 1, and as will be apparent, the operation leaves the cylinder filled with the fluid. Valve 34 is now closed and outlet valve 39 opened. Preferably this outlet is connected with the outlet on the other cylinder, and between the two is an adjustable outlet (not shown). The descent of the parts moves the piston head against the fluid in the cylinder and, as the fluid discharge is regulated, the descent of the parts may be controlled. If it is desired to supply an extraneous pressure, the valve 35 is opened and fluid under pressure admitted in front of the piston head.

In structures embodying the invention in its entirety, the weight of the press is materially cut down without sacrificing any pressing area. To this end, the main pressing members are relatively small as compared with similar devices previously known. The press includes, in connection with these main pressing members a relatively large number of supplemental pressing partitions. Although capable of various constructions, in the embodiment shown the upper corners of the platens 10, 11 carry clip-like brackets 45 which ride over side supporting frames 46 braced by blocks 47. Resting on and supported by these frames, are a large number of hanger bars 48 for supporting the press bags 49. These bags are provided with a pair of hanging tabs 50 (Fig. 3) through which the rods or bars 48 are passed to suspend the bags in place.

Located between each two adjacent press bags is a supplemental pressing partition 51. While this may be of any suitable construction, it is shown as a lattice formed of a plurality of parallel slats 52 running in one direction and a second series of similar slats 53 at right angles to the former. This makes a simple and effective pressing medium and allows for the outflow of the ex-

pressed liquid. At the bottom, the partitions have a thicker cross bar 153 (Fig. 4) which serves to clamp the bag bottoms to substantially close the same.

- 5 Means is provided for mounting the partitions in a simple, inexpensive manner and such that there is a wide range in the number of partitions which may be utilized. This is accomplished by freely suspending 10 the partitions. As here shown, (Fig. 5) the top transverse slat of each partition is extended outwardly at each end to form shoulders 253. To support the partitions, bars are provided for the shoulders 253 to rest 15 on, so arranged as to accommodate the press movement. As shown, pivoted to each side of the platen 11 is a side supporting bar 55. The opposite end of each bar is free and has a sliding support in a bracket 56 on the 20 platen 10. The partitions are suspended on these bars. The proper relative spacing of the partitions when the pressing members are raised, is maintained by link chains 54 secured at substantially equally spaced intervals 25 to the partitions, the ends being secured to the platens.

Means is provided for feeding the material to be treated to the press bags. This may be of any suitable construction. As 30 here shown, on each side of the press is a feed pipe 57 freely slideable in brackets 58 carried by the press platens. Connected with each of these pipes is a flexible hose 65 leading to the source of supply. Each bag 35 has a leading-in pipe 59, these pipes being staggered for consideration of space. This is to say, alternate bags have the leading-in pipes on the right side, the other on the left (see Fig. 5). Each leading-in pipe 59 is 40 connected by a flexible hose 60 and a valve 61 with its respective feed pipe 57.

It is noted that the construction described is such that a large number of partitions or supplemental pressing members may be 45 used; as the partitions have merely a sliding support on the side bars, thus being freely suspended. Furthermore, there is practically no dimensional limitations of the associated parts. The platens may be positioned 50 the desired distance apart, the rods 14, side bars 55, brackets 45, chains 54 and feed pipes 51 being furnished the length required. In other words, the number of supplemental pressing members which may be 55 used is not limited by any connecting or securing means or the like.

The parts being in the position of Fig. 1, the press bags are filled with the material to be treated. The pressure in the cylinder 60 being released, the press members are allowed to descend under the force of gravity. This swings the levers in such manner that the press platens are caused to move toward each other, thus pressing the material in the 65 bags between the pressing members. The

expressed liquid escapes by the latticed partitions into a collecting tank 63 from which it may be drawn off in any suitable manner. At the conclusion of the pressing operation the parts have reached the position of Fig. 2. The fluid pressure is then admitted 70 through valve 34. This causes the controlling means to swing the levers in the opposite direction, so as to raise the press members again. The hand wheels 15 are turned 75 to separate the lower ends of the platens so the bags may be emptied and the apparatus is ready for another cycle.

With the construction described, the controlling means, which floats between the 80 lever members, is free from the weight and strain of the press members, this weight and strain being taken by the pedestals and tension rods. This is especially important with the rising and falling platens, but of value, 85 also, in presses in which the pressing movements of the platens are secured without the rising and falling movement. Furthermore, as the strain of the press members is taken by the pedestals, there is no excessive 90 strain on the foundation and no unusual or specially prepared foundation is required, as only the weight of the press is to be considered and this is greatly reduced by the 95 invention.

What is claimed is:

1. In a pressing apparatus, the combination with coöperating pressing members mounted for gravitational movement downward, and means for causing the downward movement of the pressing members to bring said members closer together, of means, mounted to be free from the weight of the press, for checking the downward movement of the 100 pressing members.

2. In a pressing apparatus, the combination with coöperating pressing members mounted for gravitational movement downward, and means for connecting said pressing members for angular movement relative to 110 each other, of means, mounted to be free from the weight of the press, for moving said pressing members upward, and mechanism arranged to move the pressing members angularly toward each other during their 115 downward movement and to separate them during their upward movement.

3. In a pressing apparatus, a pair of co-operating pressing members mounted for gravitational movement downward and means 120 for connecting said pressing members for angular movement relative to each other, of mechanism arranged to move said members angularly toward each other during their downward movement and to separate them 125 during their upward movement, and means for moving said pressing members upward and for checking their descent, said means having a floating connection with the associated parts.

4. In a pressing apparatus, a pair of co-operating press members arranged to have a general up and down movement, leverage means for causing said press members to mutually approach and recede as they descend and rise, and controlling means for the press members connected with said leverage members to float therebetween.
5. In a pressing apparatus, a pair of co-operating press members pivoted to rock toward and from each other, and a controlling fluid pressure cylinder and piston mounted to float between the pressing members.
- 10 6. In a pressing apparatus, a pair of co-operating press members pivoted to rock toward and from each other, a pair of lever members connected to the press members and mounted to move the press members toward and from each other, and a controlling fluid pressure cylinder and piston having a floating connection between said lever members.
- 15 7. In a pressing apparatus, a pair of opposed press members, a pair of lever members connected to the press members and mounted to move the press members toward and from each other, and a controlling fluid pressure cylinder and piston having a floating connection between said lever members.
- 20 8. In a pressing apparatus, the combination with a pair of fulcrums, of a pair of lever members angularly movable about said fulcrums and extending toward each other, a pair of co-operating pressing members, each carried by its respective lever member, and a fluid pressure cylinder and piston having a floating connection between said lever members.
- 25 9. In a pressing apparatus, supporting pedestals for each end of the press, tension rods connecting said pedestals, a pair of co-operating press members mounted to have a general up and down movement, lever members for causing said press members to mutually approach and recede as they descend and rise, and controlling means for the press members, the whole being so mounted that the weight and strain of the parts are taken by said pedestals and tension rods.
- 30 10. In a pressing apparatus, a pair of co-operating press members arranged to have a general up and down movement, means for causing said pressing members to mutually approach and recede as they descend and rise, controlling means for said press members, said means acting in a substantially horizontal direction, and a relatively large number of supplemental pressing members associated with said first named pressing members.
- 35 11. In a pressing apparatus, a pair of co-operating pressing members arranged to have a general up and down movement, lever members for causing said pressing members to mutually approach and recede as they descend and rise, controlling means for the pressing members connected with said lever members to float therebetween, and a relatively large number of supplemental pressing members associated with said first named pressing member.
- 40 12. In a pressing apparatus, a pair of co-operating pressing members arranged to have a general up and down movement, lever members for causing said pressing members to mutually approach and recede as they descend and rise, controlling means for the pressing members associated with said first named pressing members, and a feed pipe slidably mounted along the side of said pressing members.
- 45 13. In a pressing apparatus, the combination with co-operating pressing members arranged to have a general up and down movement, lever members for causing said pressing members to mutually approach and recede as they descend and rise, a fluid pressure cylinder and piston having a floating connection between said lever members, side supporting bars, a plurality of supplemental pressing members freely suspended on said bars, and means for maintaining substantially equal intervals between said supplemental pressing members at the tops thereof when the press is in raised position.
- 50 14. In a pressing apparatus, the co-operating pressing members 10, 11, the pedestals 20 and tension rods 22, the lever members 17, 18, and the floating cylinder 27 and piston 28, the supplemental pressing members 51 having the shoulders 253, the side bars 55, the brackets 45 and the hanger bars 48, substantially as described.
- 55 15. In a pressing apparatus, the co-operating pressing members 10, 11, the pedestals 20 and tension rods 22, the lever members 17, 18, and the floating cylinder 27 and piston 28, substantially as described.
- 60 16. In a pressing apparatus, the co-operating pressing members 10, 11, the pedestals 20 and tension rods 22, the lever members 17, 18, the floating cylinder 27 and piston 28, and supplemental pressing members between the members 10, 11, substantially as described.

In testimony whereof I have hereunto set my hand.

JOHN J. BERRIGAN.
